UNITED STATES PATENT OFFICE.

EMMERICH FRISCHMUTH, OF BERLIN, GERMANY, ASSIGNOR TO THE SIEMENS & HALSKE ELECTRIC COMPANY OF AMERICA, OF CHICAGO, ILLINOIS.

PROTECTIVE OR GUARD APPLIANCE.

SPECIFICATION forming part of Letters Patent No. 635,470, dated October 24, 1899.

Application filed June 3, 1899. Serial No. 719,336. (No model.)

To all whom it may concern:

Be it known that I, EMMERICH FRISCHMUTH, a subject of the German Emperor, residing at Berlin, Germany, have invented a certain new and useful Improvement in Protective or Guard Appliances, (Case No. 194,) of which the following is a full, clear, concise, and exact description.

My invention relates to improvements in a protective or guard appliance for high-potential conductors, and has for its object the provision of means for preventing the damage and danger likely to result when a conductor or wire is accidentally brought in contact with another conductor of a high-potential circuit.

More particularly my invention is adapted to be employed in connection with trolley-wires of electrical traction systems to prevent accidents resulting from the crossing of conductors of grounded or low-potential circuits with the trolley-wire.

It has previously been the practice to prevent the contact of broken conductors with the trolley-wire by employing nets or other mechanical appliances which are designed to support any broken or misplaced conductor out of engagement and at some distance from the trolley-wire. This, however, not only involves an unsightly and somewhat expensive construction, but in addition does not perfectly guard the connected apparatuses of the neighboring circuits from accident, since even with these precautions broken conductors sometimes engage live wires, thereby frequently causing serious damage.

My invention contemplates the provision of a guard or protective conductor which is maintained in proximity to the live trolley-wire, the said conductor preferably being connected with the rail or opposing conductor of the trolley-circuit.

My invention will be more readily understood by a reference to the accompanying drawings, wherein are shown somewhat diagrammatically portions of a trolley railway-line illustrating methods of practicing my invention.

The same letter of reference is used to designate like parts in both figures of the drawings.

Referring to Figure 1, it will be seen that

the trolley-wire *a* is supported above the rails in the usual manner by means of cross-wires carried upon poles *b*. Spacing-insulators *c*, disposed at suitable distances, connect the 55 said trolley-wire with the guard-wire *d*, which is strung between and connected with the cross-wires *e*, the said insulators serving to maintain the guard-wire and trolley-wire in close proximity. In order to secure more efficient connection between the guard-wire or protective conductor *d* and the rail *f*, serving for the return-conductor for the trolley-circuit, a special conductor may extend from the pole to the rail, as shown by the dotted 60 lines. Stay-wires *g* may, if desired, be run from the trolley-wire to the terminals of the guard-wire *d*, suitable insulation *h* being interposed therebetween.

The arrangement shown in Fig. 2 is very 70 similar to that of Fig. 1, with the exception that the supporting-wires *e* are not utilized for carrying the guard-wire or conducting the current to the rail, since the terminals of the guard-wire *d* are connected by diagonal wires 75 directly with the poles, which serve also to ground the said wire or connect the same to the rail *f*. By employing this arrangement it will be seen that the protective conductor *d* may be maintained in very close proximity 80 to the trolley-wire, although insulated therefrom by the spacing-insulators *c*, disposed at suitable distances to maintain the relative positions of the wires.

By employing the spacing-insulators at frequent intervals between the guard-wire and the protected conductor the latter, it will be seen, is supported in part throughout its length by the said guard-wire, and, moreover, should the conductor break, the insulators, 90 which preferably are disposed near enough together to prevent the severed ends from reaching the ground, will accordingly serve to obviate accidents frequently resulting from the breakage of the exposed electrical conductor.

It will be understood that the guard-wires *d* need be placed in position only in localities where there is danger of accidental short-circuiting of the current—as, for example, when 100 telegraph or telephone wires are carried above the trolley-wires. When the arrangement

herein described is employed, there is practically no opportunity for a broken wire or other conductor to accidentally come in contact with the trolley-wire without also engaging the guard-wire disposed above the trolley-conductor, thus serving immediately to ground the misplaced conductor and prevent accident. By employing the spacing-insulators *c* at suitable intervals the distance between the guard and trolley wires may be very materially reduced, thus reducing the liability of accidental short-circuiting. The construction is simple, since the same cross-wire can, if desired, be employed to suspend both the guard and trolley wires and serve at the same time to connect the former with the ground or the rail-conductor, as previously explained. Moreover, the guard-wire assists in supporting the trolley-wire, and in ordinary cases this additional protective appliance may be placed in position without altering or increasing the number of supports.

At curves a side wire may be utilized as well for the purposes of a guard-wire. Somewhat more efficient protection may be secured by employing a plurality of guard-wires, which may be situated to the side of as well as above the trolley-conductor, although commonly this precaution is not necessary. Those familiar with the art will readily appreciate that the protective conductor or conductors disposed in proximity to any live insulated conductor will in many instances be found as efficient and desirable as in the precise instance herein described illustrative of my invention.

I am aware of the issue of United States Letters Patent No. 443,527, dated December 30, 1890, illustrating the employment of a particular form of guard-wire, and am also aware of the use of guard-wires in the prior art, and I do not desire to be understood as broadly claiming the use of a guard-wire in connection with electrical conductors. I believe, however, that it is novel to employ a guard-wire associated with an exposed electrical conductor, from which guard-wire the latter is separated and partially supported by means of space-insulators, which serve to maintain the relative position of the wires, said guard-wire preferably being electrically connected to the opposing conductor of the protected circuit or with the ground.

I claim, therefore, and desire to secure by 55 these Letters Patent, the following:

1. The combination with an exposed electrical conductor forming one line of a working circuit, of a guard-wire grounded or connected with the opposite line of the working circuit, and spacing-insulators uniting the said conductors and maintaining the same in close proximity to each other, substantially as and for the purpose described.

2. In a system of electrical distribution, the combination with an exposed or non-insulated conductor *a*, of a guard-conductor *d* lying in proximity thereto and connected with the opposite or return conductor of the system and spacing-insulators disposed at intervals between the said conductors adapted to maintain the same in their relative positions, substantially as and for the purpose described.

3. The combination with the trolley-conductor *a* of an electric railway, of a guard-wire *d* supported above and in immediate proximity to the said conductor by means of spacing-insulators *c* disposed at suitable intervals throughout their length, the said guard-wire being connected with the opposite or return circuit *f*, substantially as and for the purpose described.

4. In a system of electrical distribution, the combination with the exposed working conductor *a*, of sectional guard-wires *d* extending over portions of the said conductor *a* and in proximity thereto, the conductors *a* and *d* being maintained in their relative positions by means of spacing-insulators and an additional conductor uniting the protective conductor *d* with the return-circuit of the working conductor *a*, substantially as described.

5. In a system of electrical distribution, the combination with the exposed working conductor *a*, of sectional guard-wires *d* extending over portions of the said conductor *a* and in proximity thereto, the conductors *a* and *d* being maintained in their relative positions by means of spacing-insulators disposed at suitable intervals, stay-wires or supports *g* connected with and insulated from the terminals of the guard-wires *d*, and an additional conductor uniting the protective conductor *d* with the return-circuit of the working conductor *a*, substantially as described.

In witness whereof I hereunto subscribe my name this 27th day of April, A. D. 1899.

EMMERICH FRISCHMUTII.
